CLAIM

The ornamental design for a vehicle equipment mounting arm, as shown and described.

DESCRIPTION

FIG. 1 is a front, left-side, top perspective view of the vehicle equipment mounting arm;

FIG. 2 is a top plan view thereof;

FIG. 3 is a front elevational view thereof;

FIG. 4 is a left-side elevational view thereof;

FIG. 5 is a right-side elevational view thereof;

FIG. 6 is a bottom plan view thereof;

FIG. 7 is a front, right-side, bottom perspective view thereof;

FIG. 8 is a reference perspective view showing two of the vehicle equipment mounting arms attached to a storage box in an extended state;

FIG. 9 is a reference elevational view showing two of the vehicle equipment mounting arms attached to a storage box in an extended state; and,

FIG. 10 is a reference cross-sectional view showing two of the vehicle equipment mounting arms attached to a storage box in a retracted state.

The broken lines depict either unclaimed portions of the vehicle equipment mounting arm or environmental subject matter. The broken lines form no part of the claimed design.
